TRANSVERSE PILE WIRE LOOM

Harry J. Smiley, Glasgow, Va., assignor to James Lees and Sons Company, Bridgeport, Pa., a corporation of Delaware

Filed Aug. 16, 1960, Ser. No. 49,973

4 Claims. (Cl. 139—42)

This invention pertains to pile fabric looms and more particularly to an improved wire motion utilized to insert and withdraw the pile wires in a wire loom.

The present invention is a continuation-in-part of my application Serial No. 16,804, filed March 22, 1960.

The improved motion used for operating the weft-carrying needle described in my previous application has been found to be of great advantage in the operation of inserting and withdrawing the pile wires. The present disclosure carries forward this concept and describes my improved scroll drive in conjunction with a conventional wire motion on a carpet loom.

The principal object of the invention, therefore, is to provide an improved drive mechanism for the wire motion on a pile fabric loom.

A further object of the invention is to provide an improved wire motion on a pile fabric loom utilizing a walking beam carrying a double scroll sheave which oscillates back and forth on a pair of racks.

A further object of the invention is to provide an improved wire motion in which the velocity of the wires is carefully controlled at all times to permit dwell at one end of the stroke.

A further object of the invention is to provide a wire motion for a carpet loom having a double scroll drum mounted on a shaft concentrically with two pinions, a pair of horizontal racks with which the pinions mesh, and suitable driving connections for the drum whereby the drum and pinions oscillate back and forth over the racks to control the cable wound around the drum and secured to the wire box.

Further objects will be apparent from the specification and drawings in which:

FIGURE 1 is a top view of a part of a transverse wire pile fabric loom showing the wire motion incorporating the present invention.

FIGURE 2 is a front view of a part of the structure of FIGURE 1.

FIGURE 3 is a top view of the remainder of the wire motion drive of FIGURE 1.

FIGURE 4 is a front view of the structure of FIGURE 3.

FIGURE 5 is an enlarged fragmentary detail as seen at 5—5 of FIGURE 4 showing the mounting for one of the pulleys over which the cable passes.

FIGURE 6 is an exploded view showing an adjustable mounting for the rack rail.

FIGURE 7 is an enlarged transverse section as seen at 7—7 of FIGURE 4.

FIGURE 8 is a section as seen at 8—8 of FIGURE 7.

FIGURE 9 is a section as seen at 9—9 of FIGURE 7.

FIGURE 10 is an enlarged sectional detail as seen at 10—10 of FIGURE 7.

FIGURE 11 is an enlarged detail as seen at 11—11 of FIGURE 4, and

FIGURES 12—14 are diagrammatic views of the double drum and its relative positions on the racks during selected parts of the cycle.

The term "wire motion" may be used to include the entire assembly for controlling the insertion and withdrawal of the pile wires, but in the present description, it is preferred to separate the driving mechanism from the actual motion itself which comprises an oscillating hopper plate having the function of grasping individual pile

wires and inserting them separately into the shed and then withdrawing the first wire of a series of wires from the fabric in preparation for the next subsequent insertion.

Referring now more particularly to the drawings, the drive mechanism for the wire motion of a transverse wire pile fabric loom constructed in accordance with the present invention comprises a frame assembly 13 which is mounted on posts 14, 15 substantially at right angles to the path of travel of the hopper plate 16. Driving connections for the wire motion are achieved through the loom shaft 17 which is extended to terminate in a crank 18 between and in line with the posts 14, 15. However, the precise angle and location of the posts 14, 15 is immaterial insofar as the wire motion is concerned and the hopper plate velocity control mechanism may therefore be located in any position on the mill floor to which suitable driving and timing connections to the loom can be established.

20 The hopper plate 16 oscillates horizontally on the wire table 19 to insert and withdraw pile forming wires W, W from the shed of a fabric F being woven. The warp yarns of the fabric are shown schematically at 20 in FIGURE 1, the fell of the fabric at 21, and the finished fabric at 22. The pile wires W, W are used in a set of wires shown at 23 inserted in the shed of the fabric and having pile yarns selectively woven over the wires in accordance with conventional practice. The mechanism illustrated herein for controlling the pile wires 30 and withdrawing the leading wire and then re-inserting it at the back of the set 23 comprises in addition to the hopper plate 16 a wire holder 24 mounted on the hopper plate and a wire hook 25 pivotally mounted on the hopper plate and having a latch which engages in a recess on the head 26 of each wire. The hopper plate is provided with the conventional wire hook throw-out 27 and hopper pawl spring 28 and hopper brake spring 29 as shown in FIGURES 1 and 2. The conventional wire slide 30 is pivoted at 31 and oscillates back and forth to and from the broken line position shown in FIGURE 1 to the retracting position shown in full lines. When the hopper plate is all the way to the left in FIGURE 1 after the insertion of a pile wire with the wire slide in the upper position, the wire slide pivots to the full line position and the wire hook engages the wire in set 23 nearest to the front of the loom whereupon it is completely withdrawn by the righthand movement of the hopper plate whereupon the wire pivots to the broken line position and the wire is again inserted at the back 50 of set 23. The wires of the set 23 are held and retained in position in the conventional wire box 32. The hopper plate is controlled by two cables 37 and 38, one end of each cable being anchored in the cable holder 39. The retracting cable 37 is trained over a sheave 40, 55 thence around a sheave 41 journaled on an adjustable angle member 42, and bracket 43 welded to support 14 (FIG. 4). From thence cable 37 passes around a floating sheave 44 which is pivotally mounted on a bracket 45 (FIG. 5). The saddle 46 for sheave 44 is free to turn pivotally in bracket 45 on bearing 47 to which it is secured by means of lock nuts 48. The bracket 45 is also free to slide axially on shaft 50 as well as to rotate around the center of shaft 50. For this purpose the bracket is secured to a pair of bearing elements 51 and 52 having a series of bearings 53 which permit rotary oscillation and sliding of the elements 51 and 52. Shaft 50 is secured in a bracket 55 by means of collars 56, 56 and setscrews 57, 57. The bracket 55 is in turn secured to support 15 through angle 58. The construction described above in connection with the mounting of sheave 44 is important in that it provides ample freedom of movement of the sheave in the desired directions which

are induced by the change in position of cable 37 when it is wound and unwound from the double drum 60. As will be seen (FIG. 7), the cable 37 is anchored in the drum 60 by means of two capscrews 61, 61.

The advancing cable 38 is carried from cable holder 39 over and around sheave 64, then over sheave 65. Both of these sheaves 64 and 65 are journaled in brackets 66, 66 secured to the underside of wire table 19. From thence the cable 38 is trained around a sheave 67, journaled on frame element 69, and the cable then passes to the opposite side of drum 60 to be anchored by the bolts 68, 68 (FIG. 9).

The double drum 60 carries peripheral grooves 70 for accommodating each of the cables 37 and 38. In order to control the velocity of the hopper plate and to provide a suitable dwell when it is retracted, several convolutions of the groove 70 on each side of the drum are formed around a relatively smaller diameter of the drum hub 71. A scroll section 72 and 73 on each side of the drum transfers the cables from the hub diameter to the larger peripheral diameter and vice versa as is shown clearly in FIGS. 8 and 9.

The drum 60 is rigidly keyed to a shaft 74 by means of a key 75. A pair of pinions 76 and 77 are in turn keyed at the termini of shaft 74 by means of keys 78 and 79 respectively. The shaft is journaled in a bifurcated yoke 80 of walking beam 81 as shown in FIG. 7, and suitable thrust washers 82 and 83 provide an antifriction contact between the ends of hubs 71 and the innerfaces of yoke 80. Pinions 76 and 77 mesh with a pair of racks 85 and 86 which are in turn secured to the rails 87 and 88 by means of bolts 89, 89. Under control of the movement of walking beam 81 the drum 60 travels in a substantially horizontal path across the racks 85 and 86 to wind and unwind the cables 37 and 38 from the periphery of the drum. The rails 87 and 88 are adjustably anchored in supports 14 and 15 by means of saddle blocks 90, 91, 92, and 93 two of which are shown in detail in FIG. 6. The termini of rails 87 and 88 are formed with welded plates 95 and 96 and provided with horizontal slotted apertures 97, 97. The plates 95 and 96 are adjustably anchored in cooperating sockets 98 and 99 which are in turn an integral part of a weldment 100 secured to the frame members 14 and 15. Each socket 98 and 99 is provided with four adjusting screws 101, 101 which permit complete control of the lateral positioning of the rails 87 and 88. When the screws 101 have been properly adjusted, each one may be locked with its associated lock nut 102 and then the plates 95 and 96 can be securely bolted through apertures 97, 97; 103, 103. The structure of the elements 90 and 91 is identical to that of 92 and 93 and repetition in connection therewith is therefore unnecessary.

Referring now more particularly to FIGURES 4, 6, and 7, the mechanism for actuating and controlling the movement of drum 60 will be more fully described. Loom shaft 17 is journaled in a pillow block 105 and is provided with the crank 18 at its outboard end. Crank 18 is connected to the center of walking beam 81 by means of a rod 106 which is adjustable at 107 and can be locked in any adjusted position by means of a lock nut 108. Walking beam 81 is pinned at 110 to a link 111 which is in turn journaled at 112 in a pedestal 113. A second link 114 is journaled to the walking beam at 115 which is the journal for connecting rod 106. The other end of link 114 is journaled in a pillow block 116 secured to frame member 117 by means of bolts 118, 118. Link 114 is pinned to a shaft 120 in pillow block 116 by means of a pin 121. It will be observed that the distance from the center of shaft 120 to pin 115 is equal to the distance from the center of shaft 115 to the center of shaft 74. This relationship insures that each pinion 76 and 77 constantly remains in mesh with its associated rack 85 and 86 throughout the travel of the drum between the racks. Rotation of

shaft 17 imparts a modified simple harmonic motion to the drum as it travels from one end of the racks 85 and 86 to the other. The geometry of the linkage system, particularly the location and length of link 111 and pedestal 113, are designed to provide the preferred velocity curve for the drum 60 during its travel. Also, limited adjustment of the dead center position of crank 18 can be made by means of suitable setscrews 122, 122 and lock nuts 123, 123.

In operation, movement of drum 60 back and forth along the racks 85 and 86 under control of the walking beam 81 produces the correct timing and controlled velocity for the insertion of pile wires W, W into the fabric. Furthermore, the use of the rack and pinion driving elements for drum 60 permits much greater travel than would otherwise be possible except for the use of a drum having far greater diameter and therefore far greater inertia forces to be overcome. The importance of this advantage will be appreciated when it will be understood that the present wire motion can be employed on carpet looms capable of producing carpet 18 feet in width. With the drum 60 in the position shown in FIGS. 1, 3, and 4, cable 37 is wound around one side of the drum, both in the hub portion 71, the scroll portion 73, and the peripheral grooves 70. Cable 38, however, is payed out and is trained over a small portion of the hub of the drum as shown in FIG. 9 because the wire is fully withdrawn or retracted from the warp shed. As the drum is urged to the right, as seen in FIG. 4, it immediately rotates in a clockwise direction due to the action of pinions 76 and 77. This rotation of the drum slowly unwinds cable 37 from its side of the drum 60 and concurrently winds cable 38 around the hub of its side of the drum. The rate of winding and unwinding of the two cables from the drum is at all times equal. The hopper plate then moves towards the warp shed but at a slower velocity than would be the case if both cables 37 and 38 were wound around the outer periphery of the drum. However, after several turns which permit sufficient time for changing the sheds, the cables reach the scrolls 72 and 73, whereupon they are immediately transferred to the periphery of the drum and therefore rapidly accelerate the movement of the wire into the shed. When the crank 18 is turned 180°, the drum is, of course, at the opposite end of racks 85 and 86. In this position both cables 37 and 38 extend tangentially from the periphery of drum 60 but in opposite directions. This is shown to the right in FIGURE 12. Upon reversal of the direction of the drum (that is from right to left in FIG. 4) cable 37 winds rapidly and cable 38 unwinds rapidly thus withdrawing the wire from the shed at high velocity. However, since a change of direction is involved, the velocity of the drum cables and wire must pass through "0" at the reversing position. This transition, however, is made rapidly since the cables are operating from the larger drum periphery. As the wire is thus quickly retracted from the shed, the point is reached at which the cables are transferred from the outer diameter to the hub diameter which, of course, occurs after the tip of the wire W has been removed from the warp sheds. This transfer of the cables immediately decelerates the wire velocity from the peripheral velocity to hub velocity. Further deceleration, of course, is provided by the crank 18 as it approaches the opposite dead center position before reversal of direction.

FIGURE 12 shows the two extreme moved positions of drum 60 and illustrates the variation in travel path of the cable in a horizontal plane thus indicating the importance of the floating mount for pulley 44. FIGURE 13 is a schematic view which shows the comparison between the linear positions of the drum 60 on the whole racks when the cable is operating from either the hub diameter or the peripheral diameter of the drum and also during the time that the cable is being transferred from one drum diameter to the other. In the low

velocity dead center position, the drum is centered at 150. The center of the drum moves horizontally to a point shown at 151 with the cable operating in the hub grooves. The drum travels horizontally from point 151 to point 152 during the transfer of the cable from the hub to the periphery. From point 152 to 153 the cable is operating at high velocity from the periphery and until the drum returns to station 152 when the sequence reverses. The comparison between the tilting of pulley 44 as shown in FIGS. 13 and 14 shows how the floating mounting of this pulley compensates additionally for the change in elevation of the cables 37 and 38. Since the cables during one period of the cycle operate from the drum periphery and during another period of the cycle they operate from the hub periphery, this change in elevation requires a floating mount for pulley 44 which is the pulley located nearest to the drum.

It will thus be understood that I have provided an extremely efficient wire motion for a fabric loom. The use of a double rack and pinion is important in eliminating the necessity for greater cable length, larger drum diameter, greater inertia forces, and greater space requirements. The device is flexible insofar as its installation on the loom is concerned and may be mounted at right angles to the wire table as shown, or may, if desired, be mounted parallel thereto. Provided a suitable driving connection for the drum is present, any intermediate angular mounting may also be employed. The mounting of the pulleys, particularly pulley 44, cooperates to reduce the length of cable and space required.

Having thus described my invention, I claim:

1. A wire motion for a transverse wire pile fabric loom comprising a reciprocating hopper plate for carrying pile wires into the shed of a fabric being woven, a wire slide for guiding said pile wires, a retracting cable anchored at one end to the hopper plate for linearly

oscillating said hopper plate in one direction, an advancing cable anchored at one end to the hopper plate for linearly oscillating said hopper plate in the opposite direction, a cable drum having a small diameter periphery and a relatively larger diameter periphery for controlling each of said cables, means for anchoring the other end of each cable to said drum, means for transferring each of said cables to and from its associated small and large diameter drum peripheries, a shaft keyed to said drum, a pinion keyed to each end of said shaft, a rack positioned to mesh with each of said pinions, a framework for supporting said racks, a walking beam for oscillating the drum and pinions along said racks, a driving connection for said walking beam, and a plurality of sheaves for guiding the cables from the hopper plate to opposite sides of said drum.

2. Apparatus in accordance with claim 1 having a plurality of links connected to the walking beam for maintaining the meshing relationship between the pinions and the racks.

3. Apparatus in accordance with claim 1 in which at least one of the sheaves is provided with a floating mount permitting the sheave both linear and rotational movement.

4. Apparatus in accordance with claim 1 in which the framework is provided with adjusting means for the racks.
